(57) **CLAIM**

The ornamental design for a cabinet, as shown and described.

DESCRIPTION

FIG. 1 is a top, front and right perspective view of a cabinet showing my new design;

FIG. 2 is a bottom, rear and left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The evenly spaced broken lines in the drawings depict portions of the cabinet that form no part of the claimed design.

The dash-dot-dash lines depict the boundary of the claimed design and form no part thereof.

The dash-dot-dot-dash lines depict a symbolic break in length. The appearance of any portion of the cabinet between the break lines forms no part of the claimed design.
